UNITED STATES PATENT OFFICE.

JOHN A. WELTON, OF CANAL DOVER, OHIO.

FUEL-FEEDING MEANS.

1,202,628.

Specification of Letters Patent. Patented Oct. 24, 1916.

Application filed August 1, 1915. Serial No. 44,180.

To all whom it may concern:

Be it known that I, JOHN A. WELTON, a citizen of the United States, residing at Canal Dover, in the county of Tuscarawas and State of Ohio, have invented certain new and useful Improvements in Fuel-Feeding Means, of which the following is a specification.

My invention relates to certain new and useful improvements in apparatus for feeding fine fuel to furnaces and burning the same therein, and the invention consists of the parts and the constructions and combinations of parts which I will hereinafter describe and claim.

In the accompanying drawings forming part of this specification and in which similar reference characters indicate like parts in the several views; Figure 1 is a sectional view with parts in elevation of a portion of a locomotive boiler furnace showing my improved fuel feeding means in association therewith. Fig. 2 is an enlarged detail of a portion of the bottom of the coal hopper showing a couple of the controlling dampers. Fig. 2^a is a detail of one of the dampers removed. Fig. 3 is a cross section on line 3—3 of Fig. 2. Fig. 4 is an enlarged detail of a means for operating the dampers. Fig. 5 illustrates a means for operating the air shutter, 33.

The present invention has, but not necessarily, reference to a means for feeding fine fuel to furnaces substantially of the type shown and described in my former Patent No. 1,127,136, dated February 2, 1915, namely, a locomotive boiler furnace, of any approved construction and which furnace has a combustion chamber, 10, to which access is afforded through a fire-door, 11. The combustion chamber is operatively connected to a boiler, 12, of any desired type. In the combustion chamber is preferably arranged a fire-arch, 13, of fire-brick or refractory material and in which arch perforations or openings are formed through which the products of combustion escape to the space in rear of the arch, the arch being herein shown as substantially straight, although it may have other form, and being supported on circulating tubes, 14, which connect with the water-space of the boiler casing.

It will be understood that the fire-box may have any desired form and the shell or cas-

ing of the furnace may be of any design and construction well known in the art, and that the furnace is but illustrative of any furnace with which the fuel feeding features of the present invention may be operatively associated.

In the type of furnace shown, but to which specific furnace my invention is not restricted, the bottom, 15, thereof is formed of fire-brick or other refractory material having openings, 16, therethrough for the admission of air to assist combustion and which openings may also serve as escapes for ashes and cinders when the same are opened from below by means of an appropriate damper or slide, 17, having openings, 16', to register with the openings through the furnace bottom. Any other well known damper or means may be employed for the admission of the air to the fire-box without in any manner departing from the spirit of my invention, and said slide or damper is operable by a suitable lever, K, to which it is connected.

Whatever the type of furnace employed, I use in connection therewith some means for both automatically and manually controlling the feed of fuel and air to said furnace. Various agencies may be employed for this purpose. For instance, I may use a pressure regulator, A, of some suitable type connected to the steam space of the boiler and having a stem, B, which is connected to a lever, C, pivotally mounted on a floating or sliding yoke or frame, D, having a notched quadrant engaged by a spring-pressed pawl, d, adapted to rigidly lock the lever to the yoke, said lever having, also, connected to it, a valve stem, E, for operating a valve in a casing, F, which controls the passage of steam through a pipe, 37, leading to a turbine or motor which forms a part of and actuates the fuel feeding appliances which I will hereinafter describe. The stem, B, of the pressure regulator may also be connected to a rod, G, which in turn is connected to an operating lever, H, which is pivoted on a movable or floating yoke or frame, L, similar to the one before described, having a notched quadrant engaged by a spring-pressed pawl, l, adapted to rigidly lock the lever to the yoke, said lever, H, having also connected to it one end of a rod, J, whose opposite end is connected to an arm of a bell-crank or other lever, K, whose

other arm is in turn connected to the slide or damper which controls the air admission to the furnace.

Each of the levers, C and H, has a handle by which it may be manually operated, and in the length of the connecting rods, G and J, may be let a compression spring case, M, so that should the air damper be set as closed and the pressure thereafter raised, the spring in the casing would be compressed and thus the strain would be taken from the rods, and, consequently, the danger of the rods bending or breaking would be avoided.

15 By the arrangement shown or the equivalent thereof, I am enabled to automatically control the admission of air to the fire-box for combustion purposes by the boiler pressure; I am, also, enabled to perform this
20 important function manually or by the hand manipulation of the levers, C and H. The automatic and hand control of the fuel feed I also accomplish by similar means, as I will hereinafter describe.

25 The locomotive boiler furnace shown is appropriately connected to a tender or tank car having a closed tank, 20, of any suitable construction, and within which and closed by the inner top wall of the tank, is a tight
30 coal hopper, 21, into which the fuel in any desired state of subdivision may be admitted through an opening, 22. The bottom of the tight coal hopper is of substantially semi-circular form in cross section and it is provided from end to end with a series of discharges or openings, 23, substantially in the form of transverse slots and through which openings the fine coal is discharged into a
35 dust and air pipe, 24, for delivery by pneumatic or other means into the combustion chamber of the aforesaid furnace.

Within the segmental bottom of the tight coal hopper is mounted an agitating roll, 25. The form of roll shown is provided with radial blades, 26, which are designed to have a stirring and lifting effect upon the fuel in the bottom of the hopper, and thus make it possible for this fuel to be more freely discharged through the openings, 23, for delivery into the furnace. The agitating roll is mounted on a shaft, 27, on one end of which is secured a worm or other gear, 28, which is in mesh with a corresponding pinion, 29, on the end of a shaft, 30, the opposite end of which is provided with a fan, 31. This fan operates within a suitable fan casing, 32, the inner side of which is in open communication with the outer or inlet end of the dust and air pipe, 24, into which the fine fuel is delivered from the hopper. The outer side of the fan-casing, 32, is provided with a rotary or other shutter, 33, controlling openings in the casing and adapted to admit air in desired amounts to be mixed with the fuel to assist combustion, and to

act as a pneumatic means for conveying the fuel through the dust and air pipe, and through the delivery head, 34, thereof into the combustion chamber of the furnace. The shaft of the fan passes through a casing, 35, in which is mounted an appropriate turbine, 36, which is driven by steam delivered from a steam space in the boiler through a suitable pipe, 37, whereby the turbine is operated by boiler pressure and in turn operates the fan, 31, and the gears, 30 and 28, and the agitating roll, 25, said turbine casing having an appropriate pipe, 38, through which the exhaust steam may be delivered. 70 75

In order to accurately, automatically or manually control the amount of fuel delivered into the dust and air pipe, 24, I show the discharge openings in the bottom of the hopper as being controlled by suitable dampers, 39. These dampers are shown as arranged in groups and for present purposes I have illustrated the dampers as being in four groups, each damper being of substantially segmental form at the bottom and conforming to the casing and having a vertical or upstanding portion, 40, which operates in and controls the aforesaid openings, the amount of fuel discharged through the openings depending, of course, upon the degree to which the dampers are opened. Each damper has a depending arm, 41, and the dampers of each group are connected to a suitable rod, 42, the end of which is connected to one arm of a bell-crank lever, 43, the opposite arm of said lever being in turn connected to a rod, 44, which is adapted to be detachably engaged with a head, 45, on the lower end of a damper regulating mechanism for instance as that shown and described but not claimed, in my aforesaid former patent. The manner of engaging the several damper operating rods with the regulator is unimportant; in the present instance I have shown the rods, 44, as having bent ends adapted to hook into engagement with an enlarged head formed on the lower end of the regulator rod, 46, the purpose being to so detachably connect the several damper rods that any one or more sets or groups of dampers may be operated to regulate the amount of fuel fed into the dust and air pipe.

The regulation of the dampers and of the air shutter 33, connected to operate therewith may be automatic or it may be manually controlled and provision is made in the present case for both operations. That the regulation may be automatic, I propose to mount adjacent the hopper a pressure regulator, 47, which may be of any well known character, and which in the present case is connected by a pipe, 48, conducting steam from the boiler to the casing, whereby the boiler pressure is relied upon to actuate the pressure regulator and this in turn will 130

actuate those dampers, 39, which are operatively connected with the stem or rod of the pressure regulator, the amount of fuel delivered from the hopper into the dust and air pipe, however, depending upon the number of sets of dampers which are operatively connected with the rod or stem of the pressure regulator.

In the present instance I have shown the pressure regulator with a pivoted rod or stem, one part, *a*, of which is connected to a lever, 49, which is pivotally mounted on a floating yoke or frame, 50, adapted for vertical movement, and having connected to it adjacent the lower end of the rod, *a*, the upper end of a second rod, *b*, the lower part of which is fashioned in the form of an enlarged head, 45, or otherwise to better adapt it for the engagement and disengagement of the several rods, 42, which control the movements of the dampers, 39. The rod, *a*, may, if desired, have a turnbuckle, *a'*, let into its length for adjusting purposes. The floating yoke, and by floating I mean a yoke having a vertical sliding motion, provided in any suitable manner, is supplied with a segmental rack, 50', and over this operates the end of a suitable spring-pressed pawl, 51, which is mounted on the lever, 49, said lever having a handle by which it may be manually operated by the fireman or attendant. From this description it will be apparent that the operation of the pressure regulator by steam from the boiler imparts movement to the yoke, 50, and the members, *a* and *b*, thereof and which in fact constitute the stem or shaft of the regulator, 47, and the dampers, 39, are operated through movement imparted to them by the bell-crank levers, 43, and connecting rods, 42; it is equally true that the operator may grasp the lever, 49, and by a movement of the same up or down he will open or close the dampers and thus regulate the amount of fuel which is fed from the hopper into the dust and air pipe, 24.

From this description it will be understood that when the parts are in operation, the agitating roll will feed the desired amount of fine fuel into the air and dust pipe, 24, and the fan, 31, will project air into this pipe as the vehicle for carrying the fine fuel through the pipe and delivering under pressure through the head or nozzle end thereof and into the combustion chamber of the furnace. If the boiler pressure decreases and more fuel is necessary to restore the parts to proper condition, the pressure regulator, 47, will come into play in a manner well known to such devices and respond to the boiler pressure to open any one or more of the series or groups of dampers, 39, and thus increase the fuel supply. If the boiler pressure increases above the amount desired, the regulator will operate to shut off

any one or more of the groups of dampers and thus diminish the supply of fuel fed into the dust and air pipe. This regulation can, of course, as before described, be effected by a manual operation of the hand lever, 49. 70

While the pressure regulator has automatic control of the fuel at all times, there is also present the ever ready hand control, giving, also, a manual control of the fuel and air feed. 75

While I have shown and described the feeding devices as mounted on the tender of a locomotive, I do not limit the use of said devices to this location, as they may be otherwise placed; in fact the feeding devices may 80 be used in whatever connection they will be found of advantage, independent of the tender, if desired, without departing from the spirit of my invention.

It will be understood that the foregoing 85 features may be used in connection with such accessories and minor features of detail, as would be commonly employed by those familiar with the art without departing from the spirit of my invention, and that the fuel 90 feeding features herein described may be used in connection with any boiler furnace, stationary or otherwise, without departing from the scope of the invention.

The fuel dampers 39 or any number of 95 them may be of ring form in which case the upper portions 40' of these rings extend above the agitating roll to thereby serve to support some of the weight of the fuel in the hopper, while the movement of the dampers when made more or less vigorous by the operation of the hand controlling devices, will prevent any tendency of the fine fuel to pack and will cause it to be shaken down and be more uniformly fed to the furnace. 100 From the above description it will be understood that by the use of the lever, C, or its equivalent, the speed of the turbine, 36, may be increased or decreased thereby blowing into the fire box of the furnace more or less air. By the manual adjustment or operation of the levers, H and 49, I am enabled to obtain a mixture of air and coal in sufficient quantities to move the largest load, and I am permitted to utilize the exhaust steam from the engine operating the locomotive to induce an additional amount of air to enter the fire-box to complete combustion and in volume sufficient to move the largest load. This is accomplished by the adjustment of the damper, 17, which, it will be understood, is under the automatic control of the boiler pressure and also under the control of the fireman through the medium of the hand lever. 110

The arrangement is such that the speed of the turbine may be controlled by the boiler pressure to regulate the volume of air blown into the furnace by the fan and to regulate the adjustment of the dampers, 39, and consequently the fuel supply. 115 120 125 130

- 4
- ply. This same adjustment and operation is also accomplished manually through the agency of the hand levers and co-acting parts.
- 5 Having thus described my invention what I claim as new and desire to secure by Letters Patent is:—
1. In a mechanism for feeding fine-fuel, the combination with a supply hopper having fuel outlets in its lower portion, of dampers controlling the fuel outlets, connected automatic and manually-controlled means for operating the dampers and thereby regulating either automatically or by hand the feed of the fuel, and mechanism for positively conducting the fuel advanced past the dampers into the combustion chamber of a furnace, said mechanism including a blower controlled automatically and by hand.
  2. In mechanism for feeding fine-fuel, the combination with a supply hopper having fuel outlets, of dampers controlling said outlets, devices selectively connecting with the dampers for operating the latter automatically, connections in said automatic devices permitting the dampers to be operated manually, and means for positively conducting the fuel delivered past the dampers into the combustion chamber of a furnace.
  3. In a mechanism for feeding fine fuel, the combination with a supply hopper having fuel outlets, dampers controlling said outlets, means for selectively connecting the dampers in groups, means whereby any one or more of the groups of the dampers may be operated automatically, said last-named means having auxiliary connections permitting of the independent manual operation of the dampers, and means for conducting the fuel delivered past the dampers into the combustion chamber of a furnace.
  4. In mechanism of the character described, the combination with a fuel hopper having a transversely slotted bottom and dampers controlling the same, devices selectively connecting the dampers and thereby controlling the discharge of fuel from the hopper, a pneumatic conveyer for conducting the discharged material to a furnace, and means automatically controlling said damper-connecting devices, said automatic means having auxiliary connections therein providing for an independent manual control of the damper connecting devices.
  5. In mechanism of the character described, the combination of a hopper having a transversely slotted bottom and dampers controlling the same, devices selectively connecting with the dampers for controlling the discharge of fuel from the hopper, a pneumatic conveyer for conducting the discharged material to a furnace, said conveyer having an air inlet operatively connected to the damper-selective devices, and means connecting with the dampers selective devices for automatically actuating the same and thereby regulating the supply of fuel fed to the conveyer and the supply of air admitted to said conveyer, said automatic means having auxiliary connections therein providing for an independent manual control of the fuel and air supply.
  6. In a mechanism for feeding fine fuel, the combination with a supply hopper having fuel outlets, of dampers controlling the said outlets, means for connecting the dampers in groups, means whereby any one or more of the groups of dampers may be operated either automatically or manually to increase or decrease the feed of the fuel, said last-named means comprising rods each connected to a group of said dampers, levers to which the rods are connected and a fuel regulator comprising a movable yoke, a divided rod mounted therein, a lever to which the members of said rod are connected, and rods each having one end connected to a damper operating lever and having an opposite end detachably connectible with one of the members of said divided rod.
  7. In a mechanism for feeding fine fuel, the combination with a supply hopper having fuel outlets, of dampers controlling said outlets, means for operating the dampers either automatically or manually and thereby regulating the feed of the fuel, said means comprising rods each connected to a group of said dampers, bell-crank levers to one arm of which the rods are connected, a fuel regulator comprising a movable yoke and a divided rod mounted therein, a lever to which the members of said rod are connected, and means for detachably locking the lever to the yoke, said damper rods and the lower end of one of the members of the divided rod having engageable connections whereby any one or more of the groups of dampers may be rendered active or inactive at pleasure.
  8. In a mechanism for feeding fine fuel, the combination with a supply hopper having fuel outlets, groups of connected dampers controlling said outlets, means for operating the dampers either automatically or manually and thereby regulating the feed of the fuel, means whereby any one or more of the groups of dampers may be rendered active or inactive at pleasure, means carried by the dampers for agitating the fuel in the lower portion of the hopper adjacent the outlets, and means for conducting the fuel delivered past the dampers into the combustion chamber of a furnace.
  9. In a mechanism for feeding fine fuel, the combination with a supply hopper having discharge openings in its bottom, of mechanism comprising dampers controlling said discharge openings, devices selectively connected to the discharge openings and means connecting with the dampers selective devices for automatically actuating the same and thereby regulating the supply of fuel fed to the conveyer and the supply of air admitted to said conveyer, said automatic means having auxiliary connections therein providing for an independent manual control of the fuel and air supply.

connecting with the dampers whereby any one or more of the groups of dampers may be operated automatically to increase or decrease the fuel discharged from the hopper, 5 said means including auxiliary connections therein permitting of an independent manual control of the dampers, and means for positively conducting the fuel delivered past the dampers into the combustion chamber of 10 a furnace.

10. In a mechanism for feeding fine fuel, the combination with a supply hopper having a fuel discharge, of mechanism comprising dampers controlling said fuel discharge 15 and means connecting the dampers in groups, means whereby any one or more of the groups of dampers may be operated either automatically or manually to increase or decrease the fuel discharge from the hopper, 20 said last-named means including an automatic regulator having a two-part stem, a movable yoke in which the parts of the stem are mounted, said yoke having a rack surface and having a lever to which the 25 adjacent ends of the two-part stem are connected and a pawl on the lever engageable with said rack surface and releasably locking the lever to the yoke, and a tubular chamber into which the fuel is received from 30 the hopper, and means for pneumatically conducting the fuel through said tube and into the combustion chamber of a furnace.

11. The combination in an apparatus for feeding fine-fuel and air to boiler furnaces 35 having a fire-box provided with air inlets, of means controlling the admission of air into said fire-box, said means including a damper having openings to register with said air inlets, mechanism for automatically controlling the air-admission, fuel-feeding 40 mechanism connecting with the fire-box, connections automatically controlling the fuel-feeding mechanism, and means in said connections whereby both the air-admission 45 and fuel-supply may be manually-controlled.

12. In apparatus for feeding fine-fuel and air to boiler furnaces, a damper controlling the air-admission into the fire-box of a furnace, said fire-box having air inlets and said 50 chamber having openings to register therewith, connections whereby the damper is automatically controlled, means in said connections permitting the manual control of the damper, a fuel-supply and devices connecting therewith for automatically controlling the feed of fuel, and means in said last-named connections whereby the feed of fuel may be manually controlled.

13. In apparatus for feeding fine fuel and 60 air to boiler furnaces having a damper controlling the air admission into the fire-box thereof, the combination of means for automatically controlling the air admission into the fire-box, means in said connections whereby the damper may be manually con-

trolled, a fuel supply and means connected therewith for automatically controlling the feed of fuel, means in said last-named connections whereby the feed of fuel may be manually controlled, the connections controlling the air and fuel admission each comprising a regulator having a stem, a 70 movably mounted yoke having a lever to which said stem is connected, means for releasably locking the lever rigidly to said yoke, and a rod having one end connected to the yoke and having its opposite end adapted for connection to a part to be operated.

14. In apparatus for feeding fine-fuel and air to boiler furnaces, the combination of a fire-box provided with air inlets, a fuel-supply means, a pneumatic conductor for the fuel, an air-shutter controlling the admission of air to said conductor, a damper having 80 openings to register with the air inlets of the fire-box for admitting regulable quantities of air to the furnace, and a unitary mechanism producing a combined automatic and manually-controlled means for operating the fuel-supply devices, the air-shutter and the damper which controls the air-admission into the furnace.

15. The combination with a sliding damper and means automatically controlling the same, said automatic means having auxiliary connections therein permitting of an independent manual control thereof, and a yieldable connection in said controlling means to compensate for the thrust due to an automatic actuation of the latter when the auxiliary manually operated devices are in 95 locked position.

16. The combination with the fire-box of a furnace having air-inlets and a sliding 105 damper controlling the same, said damper having openings to register with said air-inlets, of a fuel-supply, means regulating the discharge of fuel, devices for automatically controlling the fuel regulating means 110 and said damper, said devices including connections permitting an independent manual control of the regulating means and damper, and a pneumatic conveyer for the fuel, said 115 conveyer having an air-inlet connected to and controlled by said combined automatic and manually controlled devices.

17. In fuel-feeding mechanism for furnaces, the combination of fuel and air-supply devices, a rotor connected to said devices, and combined and connected automatically and manually-controlled appliances controlling the speed of said rotor and thereby automatically and manually regulating both the feed of fuel and the air-supply to the furnace.

18. In fuel-feeding mechanism for furnaces, the combination of a hopper having a curved bottom with transverse slots, groups of dampers having fuel-supporting rings, a 130

feed-roll within said rings having fuel agitating elements, said dampers being movable over the curved hopper bottom and having a plurality of transverse slots adapted to 5 register with the slots in said hopper to thereby regulate the supply of fuel, a shutter-controlled conveyer comprising a casing, a fan therein, and a rotor, and a combined automatically and manually-controlled means 10 for controlling the speed of the rotor and for operating the fan and the feed-roll and thereby regulating the fuel and air supply either automatically or manually.

19. In fuel-feeding mechanism for furnaces, the combination of a hopper having a 15 curved bottom with transverse slots, a feed-

roll within said bottom, groups of dampers, said dampers being movable over the curved bottom of the hopper and having a plurality of openings adapted to register with the 20 openings in the bottom of the hopper, automatically and manually-controlled devices connected to said dampers, and means whereby the dampers may be connected to or disconnected from the automatically and 25 manually-controlled devices, said dampers having agitating elements operating in the fuel supply hopper for the purpose of preventing the fuel caking therein.

In testimony whereof I affix my signature. 30

JOHN A. WELTON.
